HEADREST

Frank G. Martin, Huntington, W. Va.

Application July 31, 1946, Serial No. 687,357

3 Claims. (Cl. 155—173)

1

This invention relates to a head rest which is particularly intended for use in beauty parlors and like establishments to rest or support the head of a person during the process of hair drying.

Several types of apparatus for drying hair on the human head have been developed. My invention does not relate to such driers, and its use is not restricted to any particular type of drier, but by way of explanation, it is pointed out that the most frequently used driers involve a hood or canopy provided with a head receiving opening in the bottom thereof. The head is placed in this opening and means are provided within the drier for subjecting the hair to heat and a drying action. The hair drying process is time consuming and in the past has been an uncomfortable ordeal. It is not possible to use conventional head rests for the reason that such head rests would disarrange the coiffure, would shield part of the hair from the drying action, and would interfere with the proper positioning of the head in the drier. It has therefore been necessary for persons undergoing hair drying to sit upright during the drying period. This position is tiresome and is made particularly so by the fact that movement of the head must be limited and controlled to prevent the hair or portions of the head from coming in contact with heated portions of the drier.

The objects of my invention are to provide a head rest which can be used without disarranging the coiffure, which does not shield the hair from the drying action, which does not interfere with the proper positioning of the head in the drier, and which permits normal turning of the head without danger of contacting the heated portions of the drier. Other objects of the invention are specifically referred to hereinafter or will be apparent from the following detailed description taken in connection with the accompanying drawings in which:

Figure 1 is a front elevation view of a head rest constructed in accordance with my invention and showing, in dotted lines, a portion of a chair to which the head rest is attached, as well as a portion of a hair drier;

Fig. 2 is a top plan view of the head rest shown in Figure 1;

Fig. 3 is a sectional view taken in the direction of the arrows along the line 3—3 of Figure 1; and

Fig. 4 is a sectional view taken in the direction of the arrows on the line 4—4 of Fig. 2.

2

The head rest comprises a base member which is designated generally by the reference numeral 5, and which is of arcuate shape, as best illustrated in Fig. 2. The base member 5 is formed of complementary track forming portions 6 and 7, which cooperate to form an arcuate track 8, which is in the form of a slot between the portions 6 and 7. The members 6 and 7 are shown as joined at their lower edges by welding, as indicated at 9. The members 6 and 7 are provided with flanges 10 and 11, respectively, near their midportions. These flanges are secured to a rigid slat 12 by welding, as indicated at 13. The slat 12 is received in a conventional clamp 14 of a beauty chair 15.

The track forming members 6 and 7, which constitute the walls of the track, are shaped to provide a depression or recess in each side wall which extends the full length of the track. The recess in the member 6 is designated by the reference numeral 16 and the comparable recess in the member 7 is designated by the reference numeral 17.

A slide member 18, also of arcuate shape, but of lesser length than the track 8, is provided with a tongue 19, which is received in the track 8. At spaced points along the tongue 19 there are apertures 20, and each of these apertures is provided with a ball 21. The balls 21 are of a diameter greater than the thickness of the tongue 19, and they extend into the recesses 16 and 17 in the side walls of the track 8. The balls thus function to prevent withdrawal of the tongue 19 from the track 8 and they also provide anti-friction means for movement of the tongue 19 along the track 8.

The slide member 18 carries resilient wire fingers 22, which are disposed at spaced points along the slide member. These fingers are preferably of relatively stiff steel wire so that they yield only slightly while supporting the head. The fingers are provided with head contacting portions 23, which are shaped to conform to the contour of the back of an average human head.

Each end of the track 8 is provided with a stop 24 for the purpose of limiting the extent of movement of the slide member 18. The stop 24 may be secured in place by means of rivets 25 or other suitable means.

A person whose hair is to be dried may occupy the chair 15, to which the head rest is attached, and may rest the head against the head contacting portions 23 of the fingers 22. These head contacting portions conform to the contour of the back of the head and as long as there is no

relative movement between the head and the fingers 22, there will be no disarrangement of the coiffure. A drier 26 of any suitable type is positioned over the head of the occupant of the chair and is appropriately adjusted. It is not necessary that the occupant of the chair sit upright. The drier 26 is adjustable to various positions, and the chair 15 may be tilted to permit the occupant to assume a reclining or semi-reclining position. Since the head contacting portions 23 of the fingers 22 conform to the contour of the head, they do not interfere with the adjustment of the drier 26. These fingers do not present any appreciable shield between the hair and the drier.

The track 8, the slide member 18, and the head contacting portions 23 of the fingers 22 all lie in arcs which have a common center at the point designated by the reference numeral 27. This point 27 lies on the normal axis of turning of the head of the occupant of the chair when that occupant is in a normal position. Because of this fact, there is no appreciable lateral, forward or rearward displacement of the head during turning. This feature of the invention is important in that it prevents the head from contacting heated portions of the drier, while at the same time permitting natural turning of the head.

I have illustrated and described what I now consider to be the preferred embodiment of my invention, but it will be obvious that various modifications may be resorted to without departing from the fundamental aspects of the invention as defined by the following claims.

Having thus described my invention, I claim:

1. A head rest for supporting the head of a person during hair drying comprising a base member provided with means for attachment to a chair and having a track which defines an arc, a slide member secured to said track for move-

ment therealong, said slide member being provided with a plurality of fingers having head contacting portions for supporting the head of a person seated in the chair, said slide member being arranged to move along said arcuate track during normal turning of the person's head without relative movement between the head contacting portions of said fingers and the head.

2. A head rest as defined in claim 1 in which said fingers are resilient wires with the head contacting portions thereof arranged to conform to the contour of the back of an average human head.

3. A head rest as defined in claim 1 in which said track is an elongated arcuate slot in said base member and said slide member is provided with a tongue extending into said slot, each side wall of said slot being provided with an elongated recess, said tongue having apertures therethrough and balls in said apertures extending into said recesses to provide anti-friction means between said tongue and said base member and to prevent withdrawal of said tongue from said slot.

FRANK G. MARTIN.
